UNITED STATES PATENT OFFICE.

WILMER J. REESER, OF BUTLER, MINNESOTA.

FOLDING CRATE.

1,005,876.

Specification of Letters Patent.

Patented Oct. 17, 1911.

Application filed July 27, 1910. Serial No. 574,146.

To all whom it may concern:

Be it known that I, WILMER J. REESER, a citizen of the United States, residing at Butler, in the county of Otter Tail and State 5 of Minnesota, have invented certain new and useful Improvements in Folding Crates, of which the following is a specification, reference being had to the accompanying drawings.

10 This invention relates to an improved folding poultry crate and has for its object to provide a collapsible metallic crate of such construction that the same may be compactly folded and nested for convenience in 15 transportation.

Another object is to provide a metallic crate of the above character which will be sanitary and may be easily and quickly cleaned.

20 A still further object resides in the provision of a simple and efficient metallic crate, of extremely durable construction and one which may be manufactured at a low cost.

25 With these and other objects in view, the invention consists of the novel features of construction, combination and arrangement of parts hereinafter fully described and claimed, and illustrated in the accompanying 30 drawings, in which—

Figure 1 is a perspective view showing the crate assembled; Fig. 2 is a similar view of the crate folded; Fig. 3 is a section taken on the line 3—3 of Fig. 1; and Fig. 4 is a section taken on the line 4—4 of Fig. 2.

Referring more particularly to the drawings 5 indicates the bottom member of the crate which is formed from sheet metal. The edge portions of this bottom plate are 40 bent upward to provide a shallow trough or pan in which a removable cardboard supplementary bottom or floor 6 is adapted to be placed. The edges of the bottom plate 5 are bent over a wire 8 to form a bead 7

45 which greatly strengthens the bottom member so that the same will retain its trough like form under the weight of the remaining sections of the crate. The sides and ends 9 and 10 respectively carry hinge straps 11

50 which are engaged upon the edge wire 7 of the bottom 5. These sides and ends of the crate are preferably perforated as shown at 12 to allow of a free circulation of air within the crate. To the outer longitudinal edges 55 of the side members 9 the top sections 13 are hinged, the hinge straps 11 having their

ends bent around a wire 14 over which the edge portions of the top sections are turned. Spaced slots 15 and 15' are formed in the top sections 13 adjacent to each end. The slots 15 which are disposed nearest the free longitudinal edges of the top sections are adapted to engage over the eyes 16 which are secured to the end member 10 and project above the upper edges thereof when in assembled position as clearly shown in Fig. 1 of the drawings. A sealing rod 17 is adapted to be passed through the eyes after the top sections are arranged in position, to securely close the crate and prevent the unauthorized opening of the same. This sealing rod is preferably formed from a length of wire, the ends of which may be twisted together and a suitable lead seal fixed thereon if desired.

60 In order to allow access to the interior of the crate without necessitating the opening of the top sections, I provide a pivoted plate 17a arranged on one of the top sections 13 which is adapted to open and close an opening 18 formed in said section. This plate is formed with a finger piece 17' by means of which it may be moved and with this finger piece a spring latch bar 19 is adapted to engage to hold the plate closed against inadvertent movement during transportation of the crate.

65 In order to secure the members of the crate in their folded or collapsed positions, an eye 20 is secured to the bottom 5 adjacent to each end thereof and is adapted to extend through the slots 15' when the sides and top sections are folded inwardly upon each other. The sealing rod 17 may then be passed 70 through the eyes to securely retain the members in their folded positions. The eyes 20 also limit the outward movement of the end sections 10 when the crate is being assembled or set up in position.

75 By providing the removable supplementary cardboard bottom 6, the crate may be kept thoroughly sanitary at all times and as it is entirely constructed of sheet metal, it will be obvious that the crate may also be easily and quickly cleansed. As shown in Fig. 2 of the drawings when the crate is collapsed and the parts secured by means of the sealing rod, the crates may be very compactly arranged or nested in large numbers for transportation thus greatly economizing 80 space. The simple construction of the device also renders the same extremely durable so

that the crates will withstand the hard usage to which they are submitted by railroad employees.

While I have shown and described the preferred embodiment of my invention, it will be understood that the same may be variously modified in its form, proportion and details of construction without departing from the essential feature or sacrificing any of the advantages of the invention.

Having thus described the invention what is claimed is:—

A collapsible crate comprising a bottom member, side and end members hinged to the edges of the bottom member, top sections hinged to the free edges of the side members, the free edges of said top sections overlapping when the crate is set up, said top sections having spaced transversely extending slots adjacent to their ends, the slots nearest

the longitudinal edges of said top sections registering when the crate is set up, eyes secured to the end members to extend through said registered slots, an eye centrally secured to each end of the bottom member and adapted to be received by the other slots in said top sections when the crate is collapsed, said latter eyes limiting the outward movement of said end members when the crate is set up, and means adapted to be positioned through said eyes to secure the sections in their assembled or collapsed positions. 25

In testimony whereof I hereunto affix my signature in the presence of two witnesses. 30 35

WILMER J. REESER.
